UNITED STATES PATENT OFFICE.

ROBERT D. PIKE, OF SAN FRANCISCO, CALIFORNIA.

APPARATUS FOR CALCINING AND CLINKERING.

Application filed July 5, 1922. Serial No. 572,395.

To all whom it may concern:

Be it known that I, ROBERT D. PIKE, a citizen of the United States, residing at the city and county of San Francisco and State of California, have invented certain new and useful Improvements in Apparatus for Calcining and Clinkering, of which the following is a specification.

The present invention relates to an apparatus for the carrying out of a continuous process of calcination and clinkering of carbonate rocks, such as calcite and magnesite, or other material subject to a similar treatment, the invention relating more specifically to an improvement in the apparatus for calcining and clinkering set forth in my pending application Serial No. 427,466, filed in the United States Patent Office under date of December the 1st, 1920, for the continuous method and apparatus for calcining and clinkering. In my said pending application, the air for supporting combustion in the calcining element of the apparatus is disclosed as passing from the cooling element directly into the rotary clinkering element of the apparatus, and from the clinkering member directly into the calcining element or member of the apparatus, discharging into said element at substantially the zone of combustion therein. The products of combustion, or the air received into the clinkering element from the cooling element, and discharging from the clinkering element directly into the calcining element for supporting combustion therein is rich in oxygen and carries therewith the CO_2 gas resulting from burning the fuel in the clinkering member, with the result that pure air is not discharged into the calcining member to support combustion. As substantially all of the air for supporting combustion in the calcining member of the apparatus set forth in my said pending application is required to pass through the rotary clinkering member thereof, of necessity the clinkering member must be of a diameter larger than that required for mere clinkering purposes. I have found that if the air passing through the cooling member or element of the apparatus be directed mainly to the combustion zone of the calcining member or element of the apparatus, and only a sufficient quantity of such air be permitted to enter the clinkering member or element at the point of combustion thereof as will support necessary combustion therein, and the products of

combustion from the said clinkering member be delivered to the calcining member at a point beyond the zone of combustion therein, that the flame temperature of combustion for the calcining member will be higher and the thermal efficiency thereof will be greater by reason of the fact that the air admitted for combustion does not have intermixed therewith CO_2 gas, and at the same time as only sufficient air is admitted from the cooling member to the clinkering member to support combustion a rotary clinkering member of smaller diameter may be utilized than the clinkering member necessary to be employed in the apparatus set forth and described in my said pending application Serial No. 427,466, and such smaller diameter clinkering member results in more efficient heat transfer from flame to clinker and in a smaller loss by radiation to the outside.

In order to comprehend the invention, reference should be had to the accompanying sheet of drawings, wherein:—

Figure 1 is a part broken side view in elevation disclosing the assembled apparatus.

Figure 2 is a part broken vertical sectional view taken through the calcining element of the apparatus disclosing the interior arrangement thereof and the disposition of the annular flue relative to said element for the discharge of the heated air of the cooler onto and over the lower hearth of the said calcining element.

Figure 3 is a part broken sectional plan view taken on the irregular line A—B Figure 2 of the drawings.

Figure 4 is a sectional plan view taken on the line C—C Figure 1 of the drawings.

In the drawings the numeral 1 is used to designate any suitable form of a vertically disposed calcining stationary element or member of the apparatus employed for the preliminary treatment of the material to be calcined and clinkered; 2 designates the rotary element of the apparatus which is employed for the clinkering of the calcined material delivered thereto as discharged from the calcining element, and 3 designates the cooling element of the apparatus, which is situated in a plane below the clinkering member 2.

The cooling member 3 receives the hot clinkered material discharging from the rotary clinkering element or member 2. In the present case, the member 1 is constructed

as a multiple hearth calcining structure for the preliminary treatment of the material, which is fed therein by any suitable form of a feeder 4. The said element 1 is provided with a series of burners 5 for the use of gaseous, liquid or pulverized fuel, which burners are situated adjacent the lower portion of the element 1 for directing flames onto and over the lower hearth of the said calcining member 1. There is interposed between the upper end of the rotary member 2 and the bottom of the member 1 a receptacle 6, which provides a receiving chamber 6' into which the products of combustion from the member 2 discharge, the said products of combustion escaping or flowing from the chamber 6' through the flues or conduits 7 which communicate with the vertically disposed flues 9 of the calcining member 1; the products of combustion moving upwardly through the flues 9 and escaping therefrom through the outlets 10 into the calcining member 1 and over the hearths therein at points above the zone of combustion of the said member 1. The calcined material discharging from the stationary calcining member 1 moves through the downwardly extended water cooled conduit 11 and discharges therefrom into the upper end of the rotating clinkering member 2. In the lower end of the clinkering member 2 is extended a burner 12 for gaseous, liquid or powdered fuel, the said burner being extended into a firing hood 13 which surrounds the lower end of the member 2, but does not rotate therewith. There is a suitable running joint provided between the said firing hood 13 and the lower end of the rotating clinkering member 2 and the upper end of said member 2 is similarly connected with the receptacle 6 of the chamber 6'. As the calcined material flows through the rotating member 2 it is subjected to the heat of the flame from the burner 12, and as the path of travel through the chamber 2 is a prolonged one, the material flowing therethrough is fully clinkered before discharge therefrom. The clinkered material discharging from the lower end of the downwardly inclined rotary clinkering member 2 passes through a downwardly extended flue 14, and is delivered therefrom in the cooling member 3, which member may be of any suitable structure. In my former application Serial No. 427,466 the cooling member is illustrated as a rotary one, while in the present case such member is illustrated of a form corresponding to that of the calcining member 1. As the material flows downwardly through the cooling member 3 the same is subjected to a counter-flowing stream of cold air passing therethrough and admitted thereto through the nozzle or air inlet 15, the cooled clinkered material discharging from the cooler 3 through the discharge spout 16, provided with a suitable seal 16'. It will be understood that the air admitted into the cooler 3 through the inlets 15 may be introduced by internal draft or supplied thereto by any suitable form of a power blower. There is extended from the cooler 3 a small conduit 18 which conveys the heated air from the cooling chamber into the firing hood 13 of the rotary clinkering member 2 for supporting combustion of the burner 12, the said conduit 18 being supplied with a damper control 19. By this means the air for supporting combustion in the rotary clinkering member is supplied in a preheated form from the cooler 3. There is also extended from the cooler 3 a conduit 20 provided with a damper control 21 and with a hopper bottom 21' for collecting dust which may be carried over by the air current from the cooler, the discharge end of the conduit 20 communicating with an annular flue 22 surrounding the lower end of the calcining element 1. The heated air of the cooler admitted into the said annular flue 22 discharges therefrom through a plurality of flues 23 extended therefrom for conveying the air onto and over the lower hearth arranged within the calcining element 1 for supporting combustion of the fuel used therein for calcination. In this manner, the air for supporting combustion is delivered as pure air to the zone of combustion of the calcining member 1, and said air is free of the CO_2 gas which is mixed with the products of combustion discharged from the rotary clinkering member 2, and which products of combustion do not enter the calciner or calcining member 1 until after combustion has occurred or taken place therein. By discharging the products of combustion from the rotary or clinkering element 2 into the calcining element 1 at points above the zone of combustion, all heat of such products of combustion is utilized in the calcining element without the CO_2 contained therein retarding combustion in the said element 1. Inasmuch as the heated air for supporting combustion of the fuel is delivered from the cooling member 3 to the zone of combustion of the calcining element 1 as pure air, the flame temperature within the calciner will be higher and the thermal efficiency therefore greater than if even a small percentage of CO_2 is mixed with the air.

By the invention of the described apparatus for calcining and clinkering of the desired material all heat units contained in the air passing through the cooling element of the apparatus are conserved and utilized to support combustion of the fuel employed in connection with the calcining element and the rotary clinkering element of the apparatus, only such portion of said air is delivered as pre-heated pure air to the combustion zone of the calcining element which

- is required for supporting combustion of the fuel used therein, while the hot products of combustion from the rotary clinkering element are delivered into the calciner element 5 at points situated above the combustion zone of said element so as not to retard combustion in the calciner by reason of the CO₂ contained therein. By reason of the invention permitting of the use of a rotary clinkering element of small diameter and which is determined by the amount of gas rather than by the amount of clinker which must be passed, there is not only a more efficient heat transfer from the flame to the clinker, 10 but smaller losses by radiation to the outside atmosphere.
- It will be understood that the inner wall surface of the rotary clinkering element, of the calcining element and the various flues— 15 where required, will be lined with suitable refractory material.
- The invention resides in utilizing the pre-heated air discharging from the cooler for the clinkered material to support combustion for the fuel of the clinkering element and the calcining element, directing a portion of such air direct to the zone of combustion for the fuel of the clinkering element and another portion thereof as pure heated air 20 to the zone of combustion for the fuel of the calcining element, and delivering the products of combustion from the clinkering element in the calcining element at points above its zone of combustion.
- The design, shape or construction of the calcining, clinkering and cooling elements is an immaterial feature of the invention, one form of such element being fully illustrated and described in my said pending application Serial No. 427,466. The only change in such constructed elements of said application being such as herein described for delivering the pre-heated air from the cooler element to the zone of combustion for 25 the fuel of the clinkering element and the calcining element and for directing the products of combustion from the clinkering element into the calcining element at points above its zone of combustion.
- I do not wish to be understood as limiting or confining the invention to the details of construction herein shown and described, but on the contrary desire and wish to be understood as claiming the invention as broadly as the state of the art will warrant. 30
- No claim is made in the present application for the method as my invention, inasmuch as the same will be set forth in an application to be filed hereafter.
- Having thus described the invention, what is claimed as new and desired to be protected by Letters Patent is:—
1. An apparatus for calcining and clinkering carbonate material, the same comprising a calcining element, a clinkering
- element and a cooling element, means for delivering the calcined material into the clinkering element without exposure to the outside atmosphere, means for delivering the clinkered material within the cooling element, burners associated with the calcining element and a burner associated with the clinkering element, means for leading one portion of the air passing through cooling into the clinkering member for supporting combustion, and another portion thereof into the calcining element within the zone of combustion therein. 70
2. An apparatus for the described purpose comprising a calcining element, a clinkering element associated therewith, and a cooling member for the clinkered material, a flue for delivering a portion of the air passing through the cooler into the clinkering member to support combustion therein 75 and a flue for delivering another portion of the air passing through the cooler into the calcining element within the zone of combustion therein. 80
3. An apparatus for the described purpose comprising a calcining element provided with a series of upwardly extending flues communicating with the interior thereof at points above the zone of combustion therein, a clinkering element associated with the calcining element and adapted to receive therefrom calcined material, means for directing the products of combustion from the clinkering element into the upwardly extending flues of the calcining element, a cooling element associated with the clinkering element for receiving clinkered material discharging therefrom, a flue for directing a portion of the air passing through the cooler into the clinkering element for supporting combustion therein, and means for directing another portion of the air passing through the cooling element into the calcining element within the zone of combustion therein. 90
4. An apparatus for the described purpose, the same comprising a calcining element provided interiorly with means for the calcination of material passing therethrough, a clinkering element associated therewith means for conveying waste heat and gases discharging from the clinkering element into the calcining element, a cooling element associated with the clinkering element, and means for conveying air from the cooling element and discharging the same into the calcining element within its zone of combustion without prior intermixture with the products of combustion of the clinkering element. 100
5. An apparatus for the described purpose, the combination with a calcining element provided with a series of upwardly extended flues communicating with the interior thereof above its zone of combustion, 110

a clinkering element associated therewith, means for conveying the products of combustion from the clinkering element to the upwardly extending flues of the calcining element, a cooling element associated with the clinkering element for receiving clinkered material therefrom, and means for conveying air from the cooling element and discharging the same into the calcining element within its zone of combustion without prior intermixture with the products of combustion of the clinkering element.

6. An apparatus for the described purpose, the same comprising a calcining element provided with upwardly extended flues communicating with the interior thereof at points above its zone of combustion,

a clinkering element, means for conveying the products of combustion therefrom into the upwardly extending flues of the calcining element, an annular flue interposed between the clinkering element and the calcining element provided with a series of outlets communicating with the interior of the calcining element within the sphere of its zone of combustion, a cooling element associated with the clinkering element, and means for conveying air directly from the cooling element into the said annular flue for discharge into the calcining element for supporting combustion therein.

In testimony whereof I have signed my name to this specification.

ROBERT D. PIKE.
